UNITED STATES PATENT OFFICE.

ADOLPH A. MIEROW, OF TACOMA, WASHINGTON.

DESIGN FOR A SPOON HOLDER.

Application filed March 25, 1922. Serial No. 1,397. Term of patent 14 years.

To all whom it may concern:

Be it known that I, ADOLPH A. MIEROW, a citizen of the United States of America, residing at Tacoma, in the county of Pierce and State of Washington, have invented a new, original, and ornamental Design for a Spoon Holder, of which the following is a specification, reference being had to the accompanying drawings, forming a part hereof.

I claim:

The ornamental design for a spoon holder as shown.

ADOLPH A. MIEROW.
